UNITED STATES PATENT OFFICE.

WILLIAM F. KEISER, OF COLUMBUS, OHIO.

DESIGN FOR A GAS-BURNER.

No. 39,966.

Specification for Design.

Patented May 4, 1909.

Application filed December 21, 1908. Serial No. 468,693. Term of patent 3½ years.

To all whom it may concern:

Be it known that I, WILLIAM F. KEISER, a citizen of the United States, residing at Columbus, in the county of Franklin and State of Ohio, have invented a new, original, and ornamental Design for Gas-Burners, of which the following is a specification, reference being had to the accompanying drawing, forming part thereof.

The figure is a side elevation showing the design of the gas burner.

I claim:

The ornamental design for a gas burner, as shown.

WILLIAM F. KEISER.

Witnesses:

C. C. SHEPHERD,
L. CARL STOUGHTON.
